UNITED STATES PATENT OFFICE.

EDGAR B. HOOVER, OF WALLA WALLA, WASHINGTON, ASSIGNOR OF ONE-THIRD TO
JAMES W. IMLAY, OF WALLA WALLA, WASHINGTON.

ORE-SEPARATOR.

1,366,660.

Specification of Letters Patent. Patented Jan. 25, 1921.

Application filed March 1, 1920. Serial No. 382,301.

To all whom it may concern:

Be it known that I, EDGAR B. HOOVER, a citizen of the United States, residing at Walla Walla, in the county of Walla Walla, and State of Washington, have invented 5 certain new and useful Improvements in Ore-Separators, of which the following is a specification.

This invention relates to ore separators 10 and has for its objects to provide a means for separating the more precious metals from the dross, the metal being contained in "concentrates":

A further object is to provide a means for 15 removing the concentrates laterally without disturbing the whole, thus with less congestion to the operation:

A further object is to provide a means for regulating the fineness of the concentrates:

20 A further object is to provide a means for storing the concentrates and a cleansing medium together, the cleansing medium keeping the concentrates in a yielding state and simultaneously providing a means for cleaning the removal mechanism.

25 With these and other objects in view reference is now had to the accompanying drawings in which—

Figure 1 is a plan view of the device with 30 part of the griddle removed;

Fig. 2 is a side and end elevation enlarged of the spraying device;

Fig. 3 is a partial longitudinal section;

Fig. 4 is a side elevation;

35 Fig. 5 is an end elevation with the frame and operating mechanism removed;

Fig. 6 is an end elevation of the device; and

40 Fig. 7 is an enlarged side elevation of the adjusting means.

Having reference to the drawings like numerals refer to like parts throughout and the numeral 1 refers to the frame of the separator which may be of angle iron as 45 shown or of any suitable material.

Between the two side pieces of the frame and attached thereto are curved riffles 2, the supporting means 3 may or may not be integral with the riffles.

50 The riffles, frame and griddle 4 constitute the sluice box with the exception of the bottom which is supplied by an endless apron 5. The riffles, frame and griddle form the subject matter of my former Patent No. 55 1,317,790 and will not be further explained.

This endless apron is made adjustable to the position shown by the dotted lines 6 in Fig. 5 by any suitable regulating means, such for instance, as that shown in Fig. 7, and is mounted to travel beneath and in 60 movable contact with the curved riffles. It operates to withdraw the contents from the sluice box laterally from the bottom thereof and consists of a canvas or other yielding belt 5 protected from wear by the strips 7 65 of leather or other suitable material which bear against the riffles.

The apron is carried by the rollers 8—9 and 10 respectively, the roller 8 being movable for the purpose of adjusting the apron 70 by the above mentioned means shown in Fig. 7.

The contact between the apron and the riffles is maintained at all times by the contact roller 11, the roller being positioned 75 below the riffles in a manner to permit the apron to pass therebetween.

Above the roller 8 (and its complemental part of the apron) is mounted a washing or spraying means consisting of a pipe 12 80 having an apron 13 positioned adjacent to the orifices 14 with which the pipe is provided. The water is supplied from any convenient source and after passing through these orifices strikes the apron forming a 85 spray which is directed against the endless apron and its load of concentrates, the concentrates thus loosened from the apron would naturally have a tendency to follow down the apron to the trough below were 90 it not for a rubber 15 which may be in the shape of a scraper as shown or a revolving brush may be used, in either case the concentrates are deflected to fall upon the chute 16. 95

The chute 16 is attached to the shaft of the roller 8 by the yoke 17 which provides for independent adjustment, at the same time the chute is movable with the roller 8 and the apron by being so attached. The 100 chute may be coated with quicksilver to form an amalgam plate and is inclined with its lower end entering the trough 18 with which it registers.

The trough 18 is positioned about the 105 lower apex of the apron as is plainly shown in Fig. 5 and has the dual purpose of containing water or other cleansing medium and also the concentrates which are finally deposited herein. 110

The water from the spraying means is continually renewing the water in the trough and as the endless apron in its travel passes through the water, any concentrates still adhering thereto after passing the spraying device and the rubber is removed falling into the trough, the endless apron now continues thoroughly cleansed for its further operation. The trough may 10 carry quicksilver if desired to pick up the loose gold, in the event that gold bearing concentrates are being handled.

Any means for operating the separator may be employed, the means shown consisting of a driving pulley 19 and chain belts 20, with the usual sprocket wheels being deemed sufficient however.

In operation the separator is set in motion by power from any suitable source and the 20 ore bearing material placed in the sluice box by shovel or other means. The griddle 4 now operates in one direction to stir the material and to pass the dross over the riffles 2, permitting the concentrates to remain 25 in the bottom against the endless apron. Now it is obvious that the higher the roller 8 is positioned with relation to the side of the sluice box the less concentrates will follow, and as the most valuable part of the 30 concentrates are on the bottom, due to its weight, the greater the degree of fineness: therefore a predetermined fineness of concentrates may be obtained by regulating the apron 5; the lower the roller and apron the 35 coarser the concentrates and conversely.

As the concentrates are withdrawn from the bottom of the sluice box, and after reaching the top of the roller 8, the spray will remove the major part thereof which falling 40 on the chute are finally delivered into the trough from whence they are recovered.

By amalgamating the chute much of the gold will be caught thereon.

The water in the trough through which 45 the apron travels keeps the concentrates in a yielding state and removes all material from the apron.

All parts herein which conflict with other 50 patents are expressly disclaimed.

Having thus described my invention, I claim—

1. In an ore separator, a sluice box, consisting of a frame, a revolving griddle, and curved riffles attached to said frame in combination with an endless apron operable in movable contact with said curved riffles, and forming the bottom of said sluice box, rollers carrying said endless apron, a means for varying the amount of contact between said 55 endless apron and said riffles, a contact roller supporting said endless apron against said curved riffles, an adjustable washing means mounted above said endless apron and adjustable therewith, a means for re- 60 moving the concentrates from said endless

apron, a chute positioned beneath said endless apron, a receiving trough, and a means for operating said endless apron and revolving griddle.

2. In an ore separator, a sluice box, consisting of a frame, a revolving griddle journaled in said frame, curved riffles attached to said frame, in combination with an adjustable endless apron in movable contact with said riffles and forming the bottom of 75 said sluice box, adjustable rollers carrying said endless apron, a means for varying the amount of contact between said endless apron and said riffles, an adjustable washing means mounted above said endless apron on its discharge side and adjustable therewith, a means for removing the concentrates from said endless apron, said means being positioned to guide said concentrates to a chute, an amalgam chute positioned to receive the concentrates from the discharge side of said endless apron, a receiving trough positioned beneath said endless apron and said chute, and a means for 80 operating said endless apron and with it 85 said revolving griddle.

3. In an ore separator, a sluice box, consisting of a frame, a revolving griddle, curved riffles attached to said frame in combination with an endless apron positioned beneath said curved riffles and in movable contact therewith, and forming the bottom of said sluice box, adjustable rollers carrying said endless apron, an adjustable washing means consisting of a spraying device positioned above said endless apron at its discharge side and adjustable therewith, a means for removing the concentrates from said endless apron, an inclined amalgam chute positioned to receive the concentrates from said endless apron, with its lower end engaging a receiving trough, said receiving trough positioned beneath said endless apron and about the lower extremity thereof, and a means for operating said endless 100 apron and said revolving griddle. 105

4. In an ore separator, the combination of a sluice box having a revolving griddle, and an endless apron operably mounted beneath said sluice box to form the bottom thereof, a means for varying the position of said endless apron with respect to said sluice box, a means for removing the concentrates from said endless apron, a trough positioned beneath and in a manner to receive said apron said trough being designed to carry water wherewith said apron is cleansed in its passage therethrough, and a means for operating said ore separator. 115 120

5. In an ore separator, the combination of a sluice box having curved riffles and a revolving griddle, and a means for withdrawing the contents laterally from the bottom of said sluice box consisting of an endless apron, said endless apron forming the 125

bottom of said sluice box, a means for regulating said apron to obtain a concentrate of a predetermined fineness, a chute positioned below said endless apron and movable there-
5 with, a trough positioned about the lower apex of said endless apron and to receive the lower end of said chute, said trough

having the dual purpose of storing a cleansing medium for said endless apron and also the concentrates, and a means for operating 10 said ore separator.

In testimony whereof I affix my signature.

EDGAR B. HOOVER.
